W. COOKE.
RAILROAD RAIL AND BASE PLATE.

No. 99,165.

Patented Jan. 25, 1870.

FIG. 1.

FIG. 2.

INVENTOR:

Watts Cooke
by B. F. James,
his Atty.

United States Patent Office.

WATTS COOKE, OF PATERSON, NEW JERSEY.

Letters Patent No. 99,165, dated January 25, 1870.

IMPROVED RAILROAD-RAIL AND BASE-PLATE.

The Schedule referred to in these Letters Patent and making part of the same.

To all whom it may concern:

Be it known that I, WATTS COOKE, of the city of Paterson, and State of New Jersey, have invented a new and useful Improvement in "Endless Railroad-Rails and Base-Plates;" and I do hereby declare the following to be a full, clear, and exact description of the construction and operation of the same, reference being had to the annexed drawings, making a part of this specification.

The nature of my invention consists in the construction of a railroad-rail, and a base-plate for its reception, so that in the event of a break in the rail itself, it shall, nevertheless, be retained in its proper position, thereby preventing the recurrence of such accidents as have become so common by reason of broken and displaced rails.

In the drawings—

Figure 1 represents a perspective view of the rail, base-plate, and fastenings.

The rail A is made in the usual form, except in this, that on the base of the rail, on its upper side, is formed a ledge d, running the whole length of the rail. This ledge may be formed on both sides of the rail, if desired.

The base-plate B is formed as shown in the drawings, and is laid continuously upon the line of the track, breaking joints with the rail itself.

On one side a flange is turned up and bent over, as seen at B', to receive the flange of rail at its base, which fits snugly into the same.

On the opposite side, a plate, C, of the same length as the base-plate, and in shape conforming to the base-flange of the rail, is placed, and held firmly in position by the spikes D, which are driven, through the base-plate B, into the ties or sleepers of the road-bed. By this construction, if a rail, from any cause, becomes broken, it is held firmly in position by reason of this mode of construction of the base-plate and its fastenings.

B' shows a flange formed upon the base-plate, and

supports and strengthens the spike D. In practice, this may be omitted, by leaving a sufficient space between the hole where the spike is driven and the edge of the base-plate, as is obvious from the inspection of the drawing.

Figure 2 is a cross-section of my invention, the same letters in each representing the same parts.

A plain bar of iron, corresponding in length to the base-plate, may be used in place of the bar C, as shown, it being only necessary to have the rail itself confined in such a manner, that, even if broken, it may retain its upright position.

By this invention, the rails can be readily and easily removed or placed in position, by simply drawing the spikes on one side of the base-plate.

The latter is made of iron or steel, receives and adjusts the rails in line, answers all the purposes of a chair, and tends to prevent vibration of the rails, and consequent injury thereto.

I do not claim a continuous railway-chair or base-plate; but

What I do claim as my invention, and desire to secure by Letters Patent, is—

1. The construction and arrangement of an "endless railroad-rail and base-plate," and supplemental plate C, in the manner, and for the purpose herein described.

2. The combination of the base-plate B with a detachable bar or plate, so that when the rail A is applied to the same, the whole may be fastened and held firmly in position by the spikes D, in the manner and for the purpose herein set forth.

3. The rail A, when it has formed upon it the projection or ledge d, when combined with the base-plate B and detachable plate C, in the manner and for the purpose herein described.

WATTS COOKE.
